(57) **CLAIM**
The ornamental design for a doll with legs and pacifier, as shown and described.

DESCRIPTION

FIG. 1 is a rear left side perspective view of a doll with legs and pacifier, showing our new design therefor;
FIG. 2 is a front right side perspective view of the doll with legs and pacifier as mirrored in FIG. 1;
FIG. 3 is a front perspective view of an alternate embodiment of the doll with legs and pacifier thereof;
FIG. 4 is a right side plan view of the doll with legs and pacifier in FIG. 1; showing the right side, the left side being a mirror image thereof;
FIG. 5 is a plan front view of the doll with legs and pacifier in FIG. 1;
FIG. 6 is a plan rear view of the doll with legs and pacifier in FIG. 1;
FIG. 7 is a top view of the doll with legs and pacifier in FIG. 1; and,
FIG. 8 is a bottom view of the doll with legs and pacifier in FIG. 1.
The broken line showing is for illustrative purposes only, and forms no part of the claimed design.
